CIGARETTE AND SAFETY MATCH HOLDER

Michael Mayer, Cleveland, Ohio

Application May 13, 1943, Serial No. 486,771

5 Claims. (Cl. 206—19.5)

The present invention relates to a cigarette and safety match holder, and has for its principal object to provide a holder which receives a package of cigarettes and which effectively holds a package of safety matches so that a match can be torn from the package and struck to light it without disturbing the match package as a whole.

This combined cigarette and match holder may be used in a variety of different places. For example, it may be secured to the steering column of an automobile, to the inside of the door of the glove compartment of an automobile, to the back of the front seat of an automobile, to an ash tray, etc.

The invention may be further briefly summarized as consisting in certain novel details of construction and combinations and arrangements of parts which will be described in the specification and set forth in the appended claims.

In the accompanying sheets of drawings illustrating several embodiments of my invention,

Fig. 1 is a perspective view of a cigarette and match holder applied to the steering column of an automobile;

Fig. 2 is a side view of the device with the cigarette package and the match package not shown;

Fig. 3 is a sectional view substantially along the line 3—3 of Fig. 2 with the steering column omitted;

Fig. 4 is a view of the device applied to the inside of the door of the glove compartment of an automobile, showing by dotted lines the open position of the door in which position a cigarette can be removed from the package and a match torn from the match package and struck;

Fig. 5 is a perspective view of the device shown in Fig. 4 with the cigarette package and match package removed;

Fig. 6 is a perspective view of the device applied to a substantially vertical support, which may be a wall or the back of the front seat of an automobile; and

Fig. 7 is a perspective view of an ash tray to which my device is applied.

Referring now to the holder illustrated in Figs. 1, 2, and 3, wherein the device is shown attached to the steering column of an automobile, the holder consists of a body 10 which may be formed from any suitable material which has the necessary firmness, such as a metal stamping, a plastic body, a cardboard body, or a stiff leather body. The body 10 has an opening 11 at the top so that a package of cigarettes 12 may be inserted therein. The lower ends 13 of the body partly en-

velop the automobile steering column 14 and are secured in position thereon by means of a clamp 15 which is considerably narrower than the body 10 and which passes through slots 16 in the body just above the parts 13 which envelop the column. The clamp 15 is adapted to be secured around the column 14 by a bolt 16a so as to securely or effectively fasten the body 10 to the column against movement thereon by vibration or otherwise. The package of cigarettes fits down into the opening 11 and its lower end rests upon the clamp 15 or upon the steering column.

The body 10 has provision on each side for securely holding a package of safety matches 17.

15 Near the bottom of the body each side is flanged outwardly and then inwardly to form a square shoulder 18, and immediately below the square shoulder 18 there is provided a beveled shoulder 19 formed by flanging the body outwardly on a

20 bevel which extends beyond the square shoulder 18 and then inwardly to a point where the lower end 13 extends about the steering column. It is to be noted further that the upper and lower faces of each square shoulder 18 are removed for 25 a distance slightly greater than the width of the package of safety matches 17, forming slots 20, while the outer face of the shoulder 18 is left intact forming a strap or bar 21 extending across the slots.

30 To insert a package of safety matches, the lower or striking part 17a of the match package is inserted from the top through the two slots 20 of the square shoulder 18 until it strikes the beveled shoulder 19, and until the striking part 17a extends below the strap 21. Then the striking part 17a is lifted out beyond the strap 21 and the package of matches is pulled upwardly somewhat with the striking part 17a on the outer side of the strap 21. The flap 17b of the match

35 package is then inserted behind the free end of the striking part 17a, as clearly shown in Fig. 1, the match package being thus normally closed.

40 It will be understood that both sides of the body are similarly formed. The match package is used in the normal manner, the flap 17b being lifted, a match being detached, the edge of the flap being inserted behind the striking part of the match package which is now in front of the strap 20, and the match being struck on the striking part 17a.

45 In automobiles having a gear shift on the steering column, there is a smaller column in front of the steering column. In that case, the cigarette and match holder will be attached to the smaller column.

As before stated, the device is not confined in its use or application to the steering column or the gear shift column of an automobile, but it is capable of being applied to various other parts of an automobile or to a wall or stand in a home.

In Figs. 4 and 5 I have shown my device applied to the inner side of the glove compartment door of an automobile. In this instance the cigarette and safety match holder is formed from a body or member 22 having a wall 23 which is on the inside of and parallel to the door 24 of the glove compartment, which door is hinged at its lower edge to the instrument panel. At its lower end the wall 23 of the body has an inwardly extending wall or flange 25 on which the bottom of the cigarette package rests, and then there is provided at the inner edge of the wall 25 an upstanding wall 26 which at its upper end is flanged outwardly toward the wall 23, as shown at 27, and is securely fastened to the outer or front wall 23. The wall 27 has an opening 28 for the insertion of a package of cigarettes 29 which package at its lower end rests upon the bottom flange or wall 25. Preferably the wall 27 is flanged downwardly as shown at 30 and is held in contact with the wall 23 by a pair of tongues 31 which extend in front of the downturned flange 30. Near the bottom and on the inner side of the body there are formed a square shoulder 32 and a beveled shoulder 33, the latter being adjacent the wall or flange 25. The wall of the square shoulder 32 is provided with two slots 32a, leaving a strap or bar 34 to receive and hold in position a package of safety matches 35 in precisely the same manner that the two packages of matches are received and held in position in the construction of Figs. 1, 2, and 3.

This device is adapted to be secured in any suitable manner to the inner side of the door 24, but in this instance the wall 23 is provided with a pair of hooks 36 which extend inwardly from the inner to the outer side of the door 24, and, if need be, the device can be held from movement on the door 24 by means of a screw 37. When the door 24 of the glove compartment is swung down to horizontal position, access may be had to the package of cigarettes and to the package of safety matches, one of which is torn from the package and struck in the same manner as previously described.

In Fig. 6 I have shown a device which may be attached to the rear of the front seat of an automobile for access by the occupants of the rear seat, or which may be attached to any plane surface, such as a wall. This device is formed from a member 38. At the top and bottom this member has two flanges 39 and 40 lying in the same plane and adapted to be secured to the surface to which it is adapted to be attached by a pair of screws 41. At the bottom of the upper flange 39 the member 38 extends outwardly at 42 and at the top of the flange 40 the member 38 extends outwardly at 43. The outwardly extending portion 42 has an opening 44 to receive a package of cigarettes, the same being adapted to rest upon the lower outwardly extending portion 43. Between the two portions 42 and 43 there is a wall 45 which is provided with means to secure a package of safety matches in the same manner as before described, namely, a square shoulder 46, a pair of slots 47 through the square shoulder, a strap 48 extending across the same and a beveled shoulder 49 which is immediately above the lower outwardly extending portion 43.

In Fig. 7 I have shown a cigarette and safety match holder having a construction such that it

may be applied to an ash tray 50 or to some other ornament adapted to rest upon a table or stand. This device is made from a single member 51, as in the case of the previously described devices. It has two parallel walls 52 and 53 joined by a pair of straps 54 between which is an opening 55 to receive a package of cigarettes, which package rests upon an extension of the ash tray. The device is adapted to be secured to the ash tray 50 or to a similar holding device by oppositely tapered flanges 56 which fit into tapered slots in the tray. Either or both of the walls 52 and 53 may be provided with means such as previously described for holding a package of safety matches, this means consisting of a square shoulder 57 having slots 58, a strap 59 extending across the same, and a beveled shoulder 60 beneath the strap and adapted to function in the same manner as the shoulders previously described.

Thus it will be seen that my combined cigarette and safety match holder is adapted to be employed in a variety of different ways or on a variety of different devices, but in each instance the holder consists of a cigarette package and safety match package holder including a shoulder which extends outwardly from the plane surface of the device, a strap across the same, and a beveled shoulder beneath the square shoulder extending outwardly beyond the strap so that when a package of safety matches is inserted behind the strap the bottom will engage the beveled shoulder and force the striking part of the match package outwardly so that it can be elevated and lie in front of the strap, whereupon the safety match package can be used in the manner in which such package is ordinarily used.

While I have shown certain embodiments of the invention, I do not desire to be confined to the precise details shown as the device may find utility for other purposes or in association with other supporting devices, and I therefore aim in my claims to cover all modifications which do not involve a departure from the spirit and the scope of my invention.

Having thus described my invention, I claim:

1. In a device which serves as a safety match holder, a wall having a strap extending along the wall outwardly thereof, an outwardly inclined shoulder immediately beneath said strap which is adapted to force the lower part of the package outwardly from the wall so that when the package is slightly elevated the striking part thereof will be in front of the strap and the package is securely held in position.
2. A device comprising a cigarette package holder and a match package holder, said device having a strap which extends outwardly beyond the wall of the cigarette package holder and having an outwardly inclined shoulder immediately beneath said strap adapted to force the striking part of the match package outwardly so that when it is slightly elevated it will lie in front of the strap so that the flap of the match package can be inserted behind the same for use in the conventional manner.

3. A combined cigarette and safety match holder comprising a single member adapted to be secured to a support and having provision for receiving a package of cigarettes, and means for receiving a package of safety matches, said means comprising a strap which extends outwardly beyond the wall of the cigarette package holder and having an outwardly inclined shoulder immediately beneath said strap adapted to force the striking part of the match package outwardly

so that when it is slightly elevated it will lie in front of the strap so that the flap of the match package can be inserted behind the same for use in the conventional manner.

4. A combined holder for a package of cigarettes and a pair of packages of safety matches comprising a single member having a pair of side walls and an opening at the top into which the package of cigarettes is adapted to be placed, each of said side walls having means for receiving a package of safety matches, said means comprising a strap which extends outwardly beyond the wall of the cigarette holder and having an outwardly inclined shoulder immediately beneath said strap adapted to force the striking part of the match package outwardly so that when it is slightly elevated it will lie in front of the strap so that the flap of the match package can be inserted behind the same for use in the conventional manner.

5. In combination with the steering column of an automobile, a combined cigarette package and match package holder, said holder comprising a member the lower ends of which are adapted to extend about and to be clamped to the steering column, said holder having an opening to receive a package of cigarettes and having on one or on each side wall means for receiving a package of safety matches, said means comprising a strap which extends outwardly beyond the wall of the holder and having an outwardly inclined shoulder immediately beneath said strap adapted to force the striking part of the match package outwardly so that when it is slightly elevated it will lie in front of the strap so that the flap of the match package can be inserted behind the same for use in the conventional manner.

MICHAEL MAYER.
